WEED PULLER

Charles E. Krupp, Evanston, Ill., and William R. Peterson, Lowell, Ind.

Application June 27, 1946, Serial No. 679,788

3 Claims. (Cl. 254—132)

1

This invention relates to a construction primarily designed for pulling weeds, but is usable for extracting other suitable objects from the ground.

Objects of the invention are: To provide a relatively simple construction; to provide a method of assembling the jaws; to provide stronger jaw structures in which gripping force is more evenly distributed; to so shape and arrange the jaws as to substantially prevent enlargement of the hole in the ground during their withdrawal action; to provide a construction having a wedging action which facilitates introduction of the grippers into the ground; to provide for partial closure of the jaws incident to the final stages of introduction of the jaws into the ground; to provide means by which the operator can sense the condition of the jaws after entry into the ground; to provide a broadened fulcrum surface as means about which the device as a whole can swing to facilitate withdrawal of the weed; to provide means whereby final gripping action is obtained by pulling the handle downwardly or toward the user, and by which continued pulling results in extraction of the weed.

An important feature relates to the proportioning of the parts so that during withdrawing or pulling action no enlargement of the hole, made in the ground by introduction of the tool, will occur. Thus, a construction is provided which will not dig up the ground to any great extent.

Objects, features and advantages of the invention will be pointed out in the description of the drawings forming a part of this application, and in said drawings.

Fig. 1 is a side elevation of the device showing in full lines the closed position of the jaws and in dotted lines their open position;

Fig. 2 is a side elevation looking toward the right side of Fig. 1;

Fig. 3 is a top plan view; and

Fig. 4 is a sectional elevation showing in full lines the fulcrum action in pulling, and showing in dotted lines the position of the jaws in the ground as before closure.

First referring to Figs. 1 and 4. The present device comprises an elongated handle 1 having fitted in a socket 2 at its lower end, a cylindrical stud or extension 3 of a jaw member 4. The parts are secured by a suitable fastening device 5.

This jaw member 4 is slotted as at 6, and passing through the slot and pivoted as at 7 to said jaw member 4 is a movable jaw member generally designated 9. A finger-like portion of the member 4 which is below the slot 6 is convexly

2

curved as at 10 on that side which is nearest the user, that is, on its outer side. The terminal gripping portion 11 of the jaw 4 is broadened as shown in Fig. 3, and has a flattened gripping

5 face 12.

The movable jaw 9 has a long substantially horizontal arm 15 and the weight of this arm acts normally to keep the jaws separated, that is, to keep the movable finger-like gripper arm 16 separated from the gripper arm 17. The lower end or gripper portion 19 of the jaw portion 16 is broadened as shown in Fig. 2, and has a flattened gripper face 20. The terminal edge surfaces of the jaws are relatively sharp to facilitate 10 the digging action. Fig. 4 shows a full-line position of the device in the act of pulling, and shows in dotted lines the position of the parts during 15 introduction of the jaws into the ground.

The arm 15 is provided with an upwardly directed fin-like extension 22, the upper foot-engaging surface of which is coplanar with a corresponding foot-engaging surface 23 of the arm (see Fig. 3) and the arm has a terminal broadened 20 portion 25 adapted to act as a fulcrum.

The degree of opening movement of the gripper elements 16, 17 is limited by the engagement of the bottom surface 26 of the arm 15 with the bottom wall 27 of the slot 6, and the relations of 25 the parts are such that ordinarily the gripper elements are preferably separated not more than three-quarters of an inch in that type of construction used for weed pulling. The relations of the fully separated arms are shown in dotted lines in the figure and it will be seen that the convexly curved surfaces 10 and 28 respectively of the jaw portions 17 and 16 act to perform a wedging action during introduction of the tool into the ground, and the shape is such as to facilitate 30 withdrawal after the weed has been gripped. The radius of curvature of the surface 28 has its center substantially in fulcrum point B.

After the tool has been thrust downwardly to assume the position shown in dotted lines in Fig. 45 4 the handle 1 is then pulled in direction of the arrow A or toward the operator, to swing the gripping jaws about the fulcrum center B of the element 25. This pull results in swinging the device upwardly about an arc approximately 50 represented by the line C, to extract the weed. Various changes in the proportion may be made and no limitation, in this respect, is intended 55 because of the particular illustration of Fig. 4. However, the principle is here illustrated that extracting movement is related to a fulcrum point of an arm of one of the jaws.

In introducing the jaws into the ground, the application of pressure against the upper surface of the arm 15 keeps the movable jaw in fully open position and thus the force used for driving the tool into the ground is also used for maintaining the jaws in open position while this driving occurs.

It is believed that the action of this device is unique in the following respects: When downward pushing on the handle in a vertical direction is continued after engagement of the foot or fulcrum portion 25 has occurred, the jaw portion 16 begins to approach jaw portion 17, that is, jaw portion 16 swings about the pivot 7, and this movement is sensed as a counterpressure against the foot of the operator. When he feels this counterpressure he promptly swings the handle 1 toward himself and jaw portion 17 swings toward jaw portion 16 and gripping occurs. As pulling on the handle continues weed-pulling is accomplished, as the whole device swings about the point B as a center. In other words, after the fulcrum element 25 engages the ground, relative motions between the parts can occur which result first in gripping action and then in pulling action. The counterpressure therefore indicates to the user that the jaws have been introduced to a sufficient depth, and in this manner the counterpressure acts as a kind of depth-gauge signaling.

Another important feature of this invention relates to a jaw construction which facilitates assembly of the jaws, thus permitting said jaws to be made separately (preferably by casting) and then assembled. Heretofore, jaws have been of scissor type in which the outer face of one jaw engages the outer face of the other; and in which a pivot or rivet connects the two for scissor action. This side-to-side engagement and the scissor action are objectionable for a number of reasons among which are: lack of strength, loosening of the pivot, and the necessity for providing laterally extending terminal gripping portions on the jaws and for providing a lug for limiting opening movements of the jaws.

In our construction the jaws are so constructed that one may be passed through an opening in the other, and then rotated and then translated to bring the jaws into a position in which a pivot can be passed through them.

For the above purpose the jaws are shaped in the following manner: The broadened terminal gripping portion 19 of the movable jaw 9 is made to have a thickness and size (spatulate shape) which adapts it to be passed edgewise through the slot 6. The jaw 9 has a first portion 29 so cross-sectionally shaped (oblong) as to be incapable of rotation in the opening 6. Thus, as shown in Fig. 4, the vertical height of portion 29 at the pivot 7 is greater than the width or horizontal dimension of the slot 6. This portion 29 has an opening 30 for the pivot 7. It also has circular bosses 31 adapted to insure proper fit and yet permit rocking motion of the pivoted jaws. The jaw 9 also has an elongated portion 32 (disposed intermediately of the portions 19 and 29) which is so cross-sectionally shaped (square) as to be capable of rotation in the opening 6. The corners of the square are perfectly rounded. The width of the portion 32, see Figure 2, in direction of the width of the slot 6 is less than the width of said slot, and this permits rotation of the portion 32 in the slot.

By the above construction, the parts can be assembled by first passing the part 19 from left

to right (Fig. 4) through the opening 6, then translating the jaw to bring the portion 32 into the opening 6, then while portion 32 is in the opening, rotating the jaw through an angle of 90° and then again translating the jaw in the same direction to bring the part 29 to the position of Fig. 4 after which the pivot 7 is passed through the openings in parts to condition the jaws for gripping action when the tool is used in the manner heretofore described.

We have produced a strong, efficient tool, which can be cheaply made and easily and quickly assembled, and which will not substantially enlarge the opening in the ground during pulling of the weed, and in which the gripping action is increased during pulling.

Having described our invention, what we claim is:

1. A device of the class described comprising, a first jaw having an opening, a second jaw having a first portion, a second intermediate portion, and a terminal third portion, the first portion being slidable and rockable in the opening, but being so shaped as to prevent rotation of the jaw about its long axis, the third portion being flat and perpendicular to the first portion and adapted to be withdrawn through the opening only after the jaw has been rotated about its long axis through an angle of ninety degrees, said second portion being adapted for rotation in said opening after translation thereinto, and a pivot normally passing through the jaw and through said first portion.
2. A device of the class described comprising, a first jaw having a narrow opening elongated in a direction lengthwise of the jaw, a second jaw having a first narrow flat portion slidably traversing the opening and rockable but not rotatable therein, a pivot passing through said jaws and narrow portion, said second jaw having a terminal portion as a second portion which can be withdrawn through the opening only after rotation of the jaw about its long axis through an angle of about ninety degrees, and said second jaw having a third portion disposed intermediately of the first and second portions and having a cross-sectional configuration which will allow it to be rotated in said opening about its long axis, whereby after the pivot is removed the second jaw can be translated in direction of its length to bring the third portion within the opening, and whereby on rotation of the jaw the second portion can be withdrawn, and whereby on reverse manipulation the second jaw can be assembled by passage through the opening to a position to receive the pivot.

3. A device of the class described comprising, a first jaw having a narrow opening elongated in a direction lengthwise of the jaw, a second jaw having a first narrow portion slidably traversing the opening and rockable but not rotatable therein about the long axis of the jaw, a pivot passing through said jaws and narrow portion, said second jaw having a terminal narrow flat gripping portion as a second portion transverse to said first portion and which can be withdrawn through the opening only after rotation of the jaw about its long axis through an angle of about ninety degrees, and said second jaw having a third portion disposed intermediately of the first and second portions and having a cross-sectional configuration which will allow it to be rotated in said opening about its long axis, whereby after the pivot is removed the second jaw can be translated in direction of its length to bring the third

portion within the opening, and whereby on rotation of the jaw the second portion can be withdrawn, and whereby on reverse manipulation the second jaw can be assembled by passage through the opening to a position to receive the pivot.
